UNITED STATES PATENT OFFICE.

ULRICH W. WALTON, OF PATON, IOWA.

MANIFOLD ACCOUNT-SHEETS.

1,248,960.

Specification of Letters Patent.

Patented Dec. 4, 1917.

Application filed December 5, 1916. Serial No. 135,104.

To all whom it may concern:

Be it known that I, ULRICH W. WALTON, a citizen of the United States, and resident of Paton, in the county of Greene and State 5 of Iowa, have invented certain new and useful Manifold Account-Sheets, of which the following is a specification.

The object of my invention is to provide manifold account sheets for use in banks or 10 other business institutions, whereby various records, for instance, the record of a depositor may be kept by a loose leaf system in duplicate.

A further object of my invention is to 15 provide means for securing the sheets together with the carbon paper between them in such a manner that when they are placed in a typewriter or other machine having a cylindrical platen, the inner sheet and carbon paper may move upon each other and 20 upon the outer sheet without wrinkling or creasing.

My invention consists in the construction, arrangement and combination of the various 25 parts of the device, whereby the objects contemplated are attained, as hereinafter more fully set forth pointed out in my claims, and illustrated in the accompanying drawings, in which:

30 Figure 1 shows a top or plan view of my improved device, the original and duplicate sheets being secured together with the carbon sheet between them, and having parts broken away to better illustrate the construction.

35 Fig. 2 shows an inverted plan view of the device.

Fig. 3 shows a sectional view of the sheets 40 shown in Fig. 1, taken on the line 3—3 of Fig. 1.

Fig. 4 shows an enlarged, detail, plan view of one corner of the duplicate sheet, showing the arrangement of the slits therein, and

45 Fig. 5 shows an enlarged, detail, plan view of one corner of the original sheet showing the arrangement of the slots and tongue thereof.

For convenience I shall explain my invention 50 as used for keeping a bank's records of its depositors' accounts by a loose-leaf system, whereby an accurate carbon copy is made which can be handed to the customer at the end of each month, or when called 55 for without the necessity of doing extra printing for the purpose of furnishing to the

depositor a statement of his account. It will be understood, however, that my improved device may be used in many business institutions other than banks.

In the illustration of my invention shown in the accompanying drawings, I have used the reference numeral 10 to indicate generally a sheet which I shall for convenience call the original sheet, used in a loose-leaf bookkeeping system and the numeral 11 to indicate a duplicate sheet. The original sheet 10 is provided with certain rulings 12 and indicating characters 13 which may be arranged in any desired way. The rulings 65 and indicating characters on the sheets may be the same. The only difference in the sheets is the lining in the coacting fastening members of the original and duplicate sheets.

It should also be understood in this connection that what I call the original sheet 70 may be used for the duplicate sheet, and what I call the duplicate sheet could be used for the original sheet.

The original sheet is provided near its top and bottom with tongues 14 cut from the sheet as clearly illustrated in Fig. 5. I prefer to use the coacting fastening device near the four corners of the sheets. The tongues 80 near the upper end of the sheet are cut along their side edges and at their upper edge so as to extend upwardly with relation to the sheet, and the tongues near the lower edge of the sheet are cut at their side edges and 85 their lower edges so as to extend downwardly with relation to the sheet. One of the lower tongues is clearly shown in Fig. 5.

The corners of the tongue 14 are preferably cut at 15 for conveniently grasping the 90 tongues for securing together the original and duplicate sheets.

The duplicate sheet is provided near each corner with a pair of horizontal, parallel 95 slits 16 of sufficient length to form a strap 17 adapted to receive the tongues 14 beneath it. The arrangement of the slots 16 is illustrated in Figs. 2 and 4.

The sheets may be arranged with similar coacting fastening devices near their side 100 edges, arranged with the slits lengthwise of the duplicate sheet, from top to bottom thereof, and with the tongues extending laterally toward the side edges of the original sheet. The coacting fastening devices at the sides 110 of the sheets are arranged near enough to the edges to permit the carbon paper to be

wide enough to be between the fastening devices at the tops and those at the bottom of the sheet, whereby the carbon is held against slipping out from between the sheets, 5 and is held properly in position. This arrangement is desirable in long sheets.

The duplicate sheet is placed face up, and the carbon sheet 18, of such size as to lie within the area between the fastening devices at the sides and tops of the sheets, is placed face down above the duplicate sheet 11. The original sheet 10 is then placed above the carbon sheet and the upper tongues 14 are inserted through the adjacent 15 slits 16, as shown in Fig. 3, and the lower tongues are similarly inserted through the lower slits 16, as illustrated in the same figure.

I have found in practice that the tongues 20 may be slightly pressed at their free ends, and will then lie flat and parallel at their free ends with the body of the original sheet 10, as shown in Fig. 3.

I will now describe the use of my device 25 and some of the advantages thereof:

With many statement machines it is the custom to have a sort of trough or receptacle adjacent to the machine and when it is desired to make statements with carbon copies 30 thereof, two sheets are taken from the receptacle, a carbon paper is placed between them, the edges of the two sheets are carefully alined and the sheets are then placed in the machine.

35 The alining of the original and duplicate sheets takes considerable time and care, and it is obvious that the placing of the carbon paper between the sheets takes the time of the machine operator and considerable length 40 of time for preparing the statements.

By providing the coacting tongues and slits in the two sheets in the manner herein set forth, the two sheets with a carbon sheet between them may be prepared or assembled 45 before the time when they are to be used, and the carbon sheet is securely held in position between the sheets when they are to be used, and the carbon sheet is securely held in position between the sheets when being 50 stored in any position, such for instance, as in vertical filing cabinets. When being used in a typewriter the slit and tongue arrangement provides for slight sliding movement for the lower portion of the sheets relative 55 to each other, as required to prevent wrinkling or creasing one of the sheets. For instance if the upper and lower edges of the sheets were rigidly secured then in passing them around a typewriter platen one of the 60 sheets would wrinkle or crease. The sheets may also readily and quickly be detached at

any time, and new under sheets substituted, because the tongues are never destroyed or folded when passing through a typewriter or when being used to attach or detach a 65 second sheet.

The arrangement of the coacting fastening devices is such that the rulings on the original and duplicate sheets are held in proper alinement when in the machine, and 70 is also such that the carbon paper is held against dropping from between the original and duplicate sheets.

The sheets may be grasped at the top and the carbon paper will not drop out and will 75 not shift about between the original and duplicate sheets.

The carbon paper is preferably longer from side to side than the distance between the tongues 14 at the corners of the sheets 80 10, but shorter than the distance between the side tongues, as illustrated in Fig. 3.

The parts herewith simply illustrate my invention and numerous changes may be made in the arrangement of the parts of the 85 device, and it is my intention to cover by the patent to be issued upon this application any forms of structure or use of equivalents which may be reasonably included within the scope of my claims. 90

I claim as my invention:

1. A manifolding device comprising a sheet, a second sheet of the same size laid thereon with its edges registering therewith, coacting locking means formed from the 95 sheets and disposed within the lines of and between the outer surfaces of said sheets whereby the edges of the first sheet may move to extend beyond the edges of the second sheet, and a carbon sheet between the 100 first described sheets and having its edges disposed adjacent to the inner edges of the locking means.

2. In a device of the class described, a sheet having a plurality of pairs of parallel 105 spaced slits of equal length adjacent to and parallel with the edges of the sheet, a carbon sheet superposed upon the first sheet and adapted to transmit impressions thereto, said carbon sheet being of such size that its edges 110 are disposed between the center of the sheet and the inner slits in the first sheet, and a second sheet of the same size as the first sheet superposed thereon and having its edges alined therewith, said last described sheet having a plurality of tongues formed 115 therefrom and each received in the two slits of one of the pairs of slits in the first sheet and extended beneath the strap formed by said slits.

Des Moines, Iowa, November 23, 1916.

ULRICH W. WALTON.
